(57) **CLAIM**

The ornamental design for a doll, as shown and described.

DESCRIPTION

FIG. 1 is a side view showing my new design for a doll, the opposite side being a mirror image thereof;

FIG. 2 is a top view thereof;

FIG. 3 is a bottom view;

FIG. 4 is a front view thereof; and,

FIG. 5 is a rear view thereof.

The portions shown in dotted lines in the Figures are for illustrative purposes only and form no part of the claimed design.
